WATER HEATER

James J. Piper, Spokane, Wash.

Application June 21, 1945, Serial No. 600,790

3 Claims. (Cl. 126—362)

1

This invention relates to a water heater and it is one object of the invention to provide a heater which may be applied to a water boiler or storage tank and has a coil associated with it through which water is circulated so that water passing through the coil, which is located in the fire box of a furnace or cook stove, will be heated and a supply of hot water stored for use when needed.

In certain parts of the country water is referred to as "hard" as it contains considerable lime. Continuous flow of such water through the heating coil causes the lime to be deposited on the inside of the coil and after a period of time the coil will become clogged by lime, thus interfering with flow of water through the coil and creating a very dangerous condition.

Therefore it is one object of the invention to provide an improved heating system whereby only a small amount of water is circulated repeatedly through the coil, thus reducing to a minimum the amount of lime which is deposited in the coil and eventually clearing the passing through the coil of lime and very effectively eliminating scaling.

Another object of the invention is to provide a heating system wherein a tank has an outer casing and an inner casing spaced from the annular wall of the outer casing to provide a water heating chamber surrounding the inner casing, there being a heating coil having its ends mounted through the wall of the outer casing and through which water circulates from a side portion of the heating chamber so that this water will be heated to a high temperature and serve to heat water in the inner chamber by heat transmitted through the wall of the inner casing.

Another object of the invention is to provide a water heating system of such construction that water is trapped in the outer heating chamber and repeatedly circulated through the coil by thermo-syphonic action.

Another object of the invention is to provide a heater which is simple in construction and may be readily applied to a storage tank of ordinary construction.

The invention is illustrated in the accompanying drawings wherein:

Fig. 1 is a view in elevation showing the improved heater connected with a storage tank for use.

Fig. 2 is a sectional view taken vertically through the heater.

Fig. 3 is a sectional view taken vertically through a heater of modified construction.

Fig. 4 is a fragmentary sectional view taken

2

transversely of a heater having an inner casing of modified form.

This heater is intended for supplying hot water to a storage tank 1 of the type used in connection with a kitchen range or a furnace for heating a house or other building. The heater consists of a tank which is disposed vertically and has its bottom 3 formed with an internally threaded neck or boss to receive a pipe 5 constituting a vertically disposed terminal for a pipe line 6 through which water is delivered into an inner chamber 1 formed within the tank 2 by an inner casing 8 disposed vertically in tank 2 and having its upper end integrally united with a disk 9 which is bolted to the outstanding flange 10 surrounding the upper end of the tank 2. It will thus be seen that the disk serves as closures for the tank 2 and the casing 8 as well as constituting means for suspending the casing in the tank in spaced relation to the annular wall and the bottom of the tank. The pipe 5 projects upwardly into the inner casing to an appreciable distance, as shown in Figure 2, and terminates at approximately the level of the lower terminal 11 of a coil 12 which is to extend into the fire box of a furnace or kitchen range and has its upper terminal 13 communicating with the tank 2 near the upper end thereof. Since the inner casing 8 is spaced from the annular wall of the outer casing or tank 2 space 14 will be provided about the inner casing and water in this space will be circulated through the coil 12 and heated to a high temperature, and the inner casing will be heated so that water within this casing will be heated. A conventional vent valve 9' is provided to allow escape of air during filling of the space 14 about the inner casing with water. The water line 6 has a T-coupling 15 interposed in it and from this coupling extends a nipple 16 which enters the bottom of the storage tank 1 so that water may be delivered to the storage tank as well as to the heater. Hot water in the inner casing 8 passes out through a pipe 17 having its upper end connected with a T-coupling 18 carried by a pipe line 19 having its inner end section 20 extending into the tank 1 through the top thereof so that hot water may be delivered from the tank through the pipe line 19 to spigots applied at terminal portions thereof.

When the heater is in use it is installed as shown in Figure 1 and the coil 12 is extended into the fire box of a furnace or cook stove. Water is delivered through pipe line 6 into the tank and into the inner casing 8 to fill the tank and the heater. A portion of the water in the heater 2

fills the space between the inner casing 8 and the wall of the main casing of the heater and this water flows into the coil 12 through the inlet 11 thereof and is heated to a high temperature before leaving the coil through the outlet 13 thereof and flowing into the upper portion of the space 14. This water is repeatedly circulated through the coil and the space 14. Water in the inner casing 8 becomes heated and this hot water is delivered from the heater through the pipe line 17 to the storage tank and flows therefrom through pipe line 19 when spigots are opened.

In Figure 3 there has been illustrated a modified construction wherein the main casing 21 of the heater has a bottom 22 through which the pipe 5 passes and an upper head 23 through which the pipe 17 passes. The inner casing 24 is formed with a head 25 having an internally threaded boss 26 at its center into which the threaded end of the pipe 17 is screwed so that the pipe 17 constitutes means for centering the upper end of the inner casing 24 in the main casing 21 as well as serving as a distributing pipe. The lower end of the inner casing is open and supported by a suitable number of legs 27 spaced from each other circumferentially of the casing. There have also been provided braces 28 for centering the lower end of the inner casing in the main casing. The coil 29 is of the helical type used in gas heaters. A conventional vent valve 23' corresponding to the vent valve 9' is provided to allow escape of air during filling of the space about the inner casing with water. If so desired the inner casing of the heater may be formed as shown in Figure 4 wherein the inner casing 30 is corrugated in order to provide additional surface and cause the water in the inner casing to be more quickly heated by contact with the wall of the inner casing.

Having thus described the invention, what is claimed is:

1. A water heater comprising a main casing closed at its top and bottom, an inner casing in the main casing closed at its top and open at its bottom and having its open lower end spaced upwardly from the bottom of the main casing, said inner casing being spaced from the wall of the main casing to provide a chamber of small capacity about the inner casing, a heating coil disposed externally of the heater with terminal portions communicating with upper and lower portions of the chamber about the inner casing, the upper terminal portion of said coil being spaced downwardly from the upper end of the inner casing and the lower terminal of the coil being spaced upwardly from the lower end of the inner casing, a water supply pipe extending upwardly through the bottom of the main casing and into the inner casing through the open lower end thereof, and an outlet pipe mounted through the top of the inner casing.

2. A water heater comprising a main casing having a bottom and having its upper end open and provided with a circumferentially extending flange, an inner casing in the outer casing spaced from the wall thereof and having its lower end open and spaced upwardly from the bottom of the main casing, a head closing the upper end of the

inner casing and having portions projecting radially therefrom and secured to said flange to close the upper end of the main casing and support the inner casing within the main casing, a supply pipe passing upwardly through the bottom of the main casing centrally thereof and into the inner casing through the open lower end thereof, an outlet pipe communicating with the inner casing through an opening in the upper head thereof, and a heating coil disposed externally of the heater and having upper and lower terminal portions mounted through the wall of the main casing at one side thereof and communicating with the space in the main casing about the inner casing, the upper terminal portion of said coil being spaced downwardly from the upper end of the inner casing and the lower terminal of the coil being spaced upwardly from the lower end of the inner casing, the lower terminal of said coil being at approximately the level of the inner end of the supply pipe.

3. A water heater comprising a main casing having a bottom and having its upper end open and provided with a circumferentially extending flange, an inner casing in the outer casing spaced from the wall thereof and having its lower end open and spaced upwardly from the bottom of the outer casing, a head closing the upper end of the inner casing having portions projecting radially therefrom and secured to said flange to close the upper end of the main casing and support the inner casing within the main casing, a supply pipe entering the main casing through the bottom thereof and extending upwardly into the inner casing through the open lower end thereof, an outlet pipe mounted through the head and communicating with the upper end of the inner casing, and a heating unit disposed outwardly of the heater at one side thereof and having upper and lower terminal portions mounted through the wall of the main casing and communicating with space in the main casing about the inner casing, the upper terminal of said heating unit being spaced downwardly from the upper end of the inner casing and the lower end of said unit being spaced upwardly from the lower end of the inner casing.
